UNITED STATES PATENT OFFICE.

GEORGE W. KITE, JR., OF HOLLYWOOD, CALIFORNIA.

THERMOSTATIC VALVE.

Application filed March 22, 1926. Serial No. 96,536.

This invention relates to improvements in thermostatic valves adapted to be used in connection with boilers, water heaters and the like.

5 An object of this invention is to provide a thermostatic valve of improved construction which is designed to overcome certain disadvantages found to exist in thermostatic valves of the prior construction and which 10 will insure that the valve will operate and will not bind.

Another object of this invention is to provide an improved thermostatic valve, in which the parts and particularly the casing 15 are so constructed that the valve may be easily and quickly adjusted without throwing the valve out of adjustment when the parts are assembled after adjustment.

With the foregoing and other objects in 20 view which will be made manifest in the following detailed description and specifically pointed out in the appended claims, reference is had to the accompanying drawings for an illustrative embodiment of the invention, wherein:

Figure 1 is a vertical section through the improved thermostatic valve,

Fig. 2 is a vertical section taken upon the line 2—2 of Fig. 1,

30 Fig. 3 is a horizontal section taken on the line 3—3 of Fig. 1, and

Fig. 4 is a perspective view of the mechanism constituting a feature of the invention, which causes the ball forming the valve closure to snap or jump from fully closed to 35 fully open position.

Referring to the accompanying drawings wherein similar reference characters designate similar parts throughout, the improved valve consists of a casing or housing having a top wall 10, a bottom wall 11, a back wall 12, end walls 13 and 14, and a removable front wall 15. The front wall 15 is detachably secured to the casing by means 40 of screws 16 which are screwed into lugs 17 formed on the top, bottom and end walls. Adjacent the end wall 13 there is formed on the casing an upstanding tubular part 18, into the upper end of which is threaded a tube 19. The tube 19 has its upper end closed and is preferably formed of copper or such material which is a good conductor of heat and which will expand materially when heated. A rod 20, preferably formed of 45 steel or other material, has its upper end bearing against the top of the copper tube 50 into the upper end of which is threaded a tube 19. The tube 19 has its upper end closed and is preferably formed of copper or such material which is a good conductor of heat and which will expand materially when heated. A rod 20, preferably formed of steel or other material, has its upper end bearing against the top of the copper tube 55 into the upper end of which is threaded a tube 19. The tube 19 has its upper end closed and is preferably formed of copper or such material which is a good conductor of heat and which will expand materially when heated. A rod 20, preferably formed of steel or other material, has its upper end bearing against the top of the copper tube 60 into the upper end of which is threaded a tube 19. The tube 19 has its upper end closed and is preferably formed of copper or such material which is a good conductor of heat and which will expand materially when heated. A rod 20, preferably formed of steel or other material, has its upper end bearing against the top of the copper tube 65 into the upper end of which is threaded a tube 19. The tube 19 has its upper end closed and is preferably formed of copper or such material which is a good conductor of heat and which will expand materially when heated. A rod 20, preferably formed of steel or other material, has its upper end bearing against the top of the copper tube 70 into the upper end of which is threaded a tube 19. The tube 19 has its upper end closed and is preferably formed of copper or such material which is a good conductor of heat and which will expand materially when heated. A rod 20, preferably formed of steel or other material, has its upper end bearing against the top of the copper tube 75 into the upper end of which is threaded a tube 19. The tube 19 has its upper end closed and is preferably formed of copper or such material which is a good conductor of heat and which will expand materially when heated. A rod 20, preferably formed of steel or other material, has its upper end bearing against the top of the copper tube 80 into the upper end of which is threaded a tube 19. The tube 19 has its upper end closed and is preferably formed of copper or such material which is a good conductor of heat and which will expand materially when heated. A rod 20, preferably formed of steel or other material, has its upper end bearing against the top of the copper tube 85 into the upper end of which is threaded a tube 19. The tube 19 has its upper end closed and is preferably formed of copper or such material which is a good conductor of heat and which will expand materially when heated. A rod 20, preferably formed of steel or other material, has its upper end bearing against the top of the copper tube 90 into the upper end of which is threaded a tube 19. The tube 19 has its upper end closed and is preferably formed of copper or such material which is a good conductor of heat and which will expand materially when heated. A rod 20, preferably formed of steel or other material, has its upper end bearing against the top of the copper tube 95 into the upper end of which is threaded a tube 19. The tube 19 has its upper end closed and is preferably formed of copper or such material which is a good conductor of heat and which will expand materially when heated. A rod 20, preferably formed of steel or other material, has its upper end bearing against the top of the copper tube 100 into the upper end of which is threaded a tube 19. The tube 19 has its upper end closed and is preferably formed of copper or such material which is a good conductor of heat and which will expand materially when heated. A rod 20, preferably formed of steel or other material, has its upper end bearing against the top of the copper tube 105 into the upper end of which is threaded a tube 19. The tube 19 has its upper end closed and is preferably formed of copper or such material which is a good conductor of heat and which will expand materially when heated. A rod 20, preferably formed of steel or other material, has its upper end bearing against the top of the copper tube 110 into the upper end of which is threaded a tube 19. The tube 19 has its upper end closed and is preferably formed of copper or such material which is a good conductor of heat and which will expand materially when heated. A rod 20, preferably formed of steel or other material, has its upper end bearing against the top of the copper tube

used in connection with the burner, although this hole is optional.

The operation of the improved thermostatic valve is as follows: In the position of 5 the valve shown in the drawing, the tube 19 is relatively cool, and gas or fuel is passing through the casing beneath the ball 29 and through the outlet 27, supplying the burner and heating the water or other substance to be 10 heated. When this water or other substance is heated beyond the desired degree, the copper tube 19 expands and the rod 20 is lifted slightly by means of the coil spring 39 bearing against the under side of the 15 lever 22, keeping the upper end of the rod in engagement with the top of the tube 19. Such upward movement of the lever, however, causes the ball 29 to be forced downwardly between the plates 31 and 32, and as 20 soon as the diameter of the ball 29 passes beneath the knife edges on the plates 31 and 32 the coil springs 35 urge the plates toward each other and thus serve to snap the ball 29 against the seat 28, shutting off the supply 25 of fuel to the burners, and allowing the water or other substance to cool. When the water has cooled below the predetermined degree, the copper tube 19 contracts and causes the rod 20 to press the lever 22 downwardly against the action of the coil spring 39. Such downward movement of the lever 22 causes the knife edges on the plates 31 and 32 to slide downwardly upon the ball 29, and as soon as they are below the horizontal 35 diameter of the ball, they will be drawn toward each other, snapping the ball 29 upwardly against the bottom of the adjusting screw 36.

In this manner the thermostatic valve 40 will serve to keep the water or substance heated at a practically constant temperature. This temperature can be varied by adjusting the adjusting screw or plug 24. The adjusting screw 36 serves to take up any 45 loose play between the lever 22 and the rod 20, and also varies the quantity of gas or fuel which may pass through the casing when the valve is in its open position. The improved thermostatic valve has several advantages over prior constructions. Heretofore it has been common practice to use instead of the plates 31 and 32 a circular coil spring, which is disposed within the slot 30. Such springs which serve the same purpose 55 as the plates 31 and 32 are disadvantageous for the reason that they tend to bind upon the ball 29, and frequently the ball gets stuck. Furthermore, when the throw or jump of the ball 29 is a considerable 60 distance, the coil spring tends to contract too much, so that the ball cannot jump or snap from one position to the other. By the improved construction the knife edges decrease the frictional engagement with the 65 ball so that it may be easily snapped from

one position to the other, and by the arrangement of the plates it will be noted that the plates cannot be contracted beyond a predetermined degree, thus insuring that the ball will never become bound or stuck.

Another advantage of the improved construction resides in having a removable front wall 15. By means of this construction the front wall can be removed and the valve adjusted. Furthermore, the valve may be operated several times by the person adjusting it to see that it operates properly. After the valve has been properly adjusted, the front wall 15 can be again applied and such application will in no way throw the valve out of adjustment. In prior constructions, however, the casing has been so constructed that this trial operation of the valve is practically impossible, and furthermore the re-assembly of the casing after the valve has been adjusted will throw the valve out of adjustment.

It will also be noted that if for any reason the rod 20 should become damaged or warped, this rod can be replaced without requiring the disassembly of the complete valve or its removal from the heater or boiler with which it is associated. This can be accomplished by removing the plug or adjusting screw 24 and swinging the lever 22 laterally. The rod 20 can then be withdrawn from within the copper tube 19 and the casing by allowing it to fall through the hole in the bottom 11 occupied by the plug 24. This permits the replacement or repair of the rod 20, and if the copper tube 19 is extending into the boiler or water heater, it is not necessary to remove the valve and drain out the water from the boiler or water heater.

From the above described construction it will be appreciated that a novel thermostatic valve has been provided having several advantages over those heretofore employed.

It will be understood that various changes may be made in the detail of construction without departing from the spirit or scope of the invention as defined by the appended claims.

I claim:

1. In a thermostatic valve, a valve seat, a lever adapted to move toward and away from said seat, means for moving said lever according to variations of temperature, a ball adapted to pass through said lever, rigid members on the lever, and means urging said rigid members into engagement with the ball so that they may cause the ball to snap from one side of the lever to the other upon movement of the lever.

2. In a thermostatic valve, an apertured member, means for moving said member in accordance with temperature variations, a ball movable through the aperture in the member, plates slideable upon the member adjacent the aperture, spring means urging

said plates toward the ball, and a seat upon which said ball is adapted to seat, whereby upon movement of said member said ball may be snapped by said plates toward or 5 away from said seat.

3. In a thermostatic valve, a horizontally bifurcated member having an aperture therethrough, means for moving said member in accordance with variations of temperature, 10 notched plates slidable in the slot on said member, springs connected to the remote edges of said plates urging them toward each other with the notches registering with the aperture, a ball capable of passing 15 through the aperture and between the plates by forcing the plates apart, a seat for the ball upon one side of the member, and means providing a stop for the ball on the other side of the member, whereby when said 20 member is moved slightly, said ball is snapped from the position engaging the seat into engagement with the stop, or vice versa.

4. In a thermostatic valve, a horizontally bifurcated member having an aperture therethrough, means for moving said member in accordance with variations of temperature, notched plates slidable in the slot on said member, springs connected to the remote edges of said plates urging them toward 30 each other with the notches registering with the aperture, a ball capable of passing through the aperture and between the plates by forcing the plates apart, a seat for the ball upon one side of the member, and means 35 providing a stop for the ball on the other side of the member, whereby when said member is moved slightly, said ball is snapped from the position engaging the seat into engagement with the stop, or vice versa, 40 said stop being adjustable as and for the purpose described.

5. A thermostatic valve comprising a casing, a fuel inlet and outlet to and from the casing, a heat expansible member on the casing, a rod movable thereby extending into the casing, a lever fulcrumed in the casing having a bifurcated apertured end disposed over the outlet, said lever being adapted to be actuated by said rod upon expansion or 45 contraction of said heat expansible member, a ball capable of passing through the aperture in said lever, notched plates slidable in the slot of the lever, spring means urging them into engagement with the ball, and an 50 adjustable stop on the casing on the opposite side of the lever from the outlet, whereby when the heat expansible member is expanded or contracted, said lever will be actuated, enabling said notched plates to snap 55 the ball into engagement with the outlet or stop. 60

6. A thermostatic valve comprising a casing, a fuel inlet and outlet to and from the casing, a heat expansible member on the casing, a rod movable thereby extending into 65

the casing, a lever fulcrumed in the casing having a bifurcated apertured end disposed over the outlet, said lever being adapted to be actuated by said rod upon expansion or contraction of said heat expansible member, 70 a ball capable of passing through the aperture in said lever, notched plates slidable in the slot of the lever, spring means urging them into engagement with the ball, and an adjustable stop on the casing on the opposite 75 side of the lever from the outlet, whereby when the heat expansible member is expanded or contracted, said lever will be actuated, enabling said notched plates to snap the ball into engagement with the outlet or stop, said 80 plates having their notched portions sharpened to knife edges.

7. A thermostatic valve comprising a casing, a fuel inlet and outlet to and from the casing, a heat expansible member on the casing, a rod movable thereby extending into the casing, a lever fulcrumed in the casing having a bifurcated apertured end disposed over the outlet, said lever being adapted to be actuated by said rod upon expansion or contraction of said heat expansible member, 85 a ball capable of passing through the aperture in said lever, notched plates slidable in the slot of the lever, spring means urging them into engagement with the ball, and an adjustable stop on the casing on the opposite side of the lever from the outlet, whereby when the heat expansible member is expanded or contracted, said lever will be actuated, enabling said notched 90 plates to snap the ball into engagement with the outlet or stop, said casing having a removable front wall enabling trial operation of the valve and the replacement of the front wall without throwing the valve out of 95 adjustment. 100

8. In a thermostatic valve, a valve seat, a member adapted to move toward and away from said valve seat, means for moving said member in accordance with variations of 110 temperature, a valve closure movable through said member and adapted to seat upon the valve seat, rigid members engageable upon the sides of the valve closure, and means for yieldably holding the rigid members in engagement with the valve closure, 115 said valve closure being larger near the points of engagement of the rigid members than elsewhere, whereby upon a slight movement of said member, the valve closure may 120 be snapped from seating position to unseating position or vice versa. 125

9. In a thermostatic valve, a valve seat, a member adapted to move toward and away from said valve seat, means for moving said member in accordance with variations of 130 temperature, a valve closure adapted to seat upon the valve seat, said valve closure being larger in one horizontal plane than in others, a rigid member movably mounted upon said

member, and means for yieldably holding said rigid member in engagement with the valve closure adjacent the largest portion thereon, whereby when said member is lightly moved, the valve closure may be snapped by the rigid member from seating position to unseating position or vice versa.

10. In a thermostatic valve, a valve seat, a member adapted to move toward and away from said valve seat, means for moving said member in accordance with variations of temperature, a ball constituting a valve clo-

sure adapted to seat upon said seat, and two notched rigid members mounted upon said member and arranged upon opposite sides 15 of the ball, at least one of said members being movable and being yieldably held in engagement with the side of the ball, whereby when said member is slightly moved, the ball may be snapped from seating position 20 to unseating position or vice versa.

In testimony whereof I have signed my name to this specification.

GEO. W. KITE, JR.
